(57) **CLAIM**

The ornamental design of a cord management system, as shown and described.

DESCRIPTION

FIG. 1 is an enlarged perspective view of the cord management system, with one of the holders removed for clarity and shown in a position of use;

FIG. 2 is a reduced scale perspective view from the other side of the cord management system of FIG. 1, shown in an alternate position of use;

FIG. 3 is a top plan view of the cord management system of FIG. 2;

FIG. 4 is a bottom plan view of the cord management system of FIG. 2.

FIG. 5 is a left side elevation view of the cord management system of FIG. 2, with the right side elevation view being a mirror image of the left side elevation view.

FIG. 6 is a front elevation view of the cord management system of FIG. 1.

FIG. 7 is a reduced scale perspective view of the cord management system of FIG. 2, shown separated from the housing portion of the invention for clarity of illustration; and, FIG. 8 is a rear elevation view of the cord management system of FIG. 2.

The broken lines showing the cord or cable are for illustrative purposes only, and do not form part of the claimed invention.
